FIRE ALARM

Ivar O. Moberg, Lowell, Mass.

Application January 3, 1946, Serial No. 638,835

2 Claims. (Cl. 177—311)

1

This invention relates to automatic fire alarms and fire alarm systems of a type suitable for use in dwellings and other buildings in which elaborate forms of apparatus of this character are too expensive to be afforded. It is an important object of this invention, therefore, to devise an exceptionally simple apparatus of this character which can be manufactured and installed economically, but which will be thoroughly practical and reliable.

The nature of the invention will be readily understood from the following description when read in connection with the accompanying drawings, and the novel features will be particularly pointed out in the appended claims.

In the drawings,

Fig. 1 is a front elevation of a preferred form of fire alarm embodying this invention;

Fig. 2 is a side elevation of the apparatus shown in Fig. 1;

Fig. 3 is a diagrammatic view of a system embodying features of this invention;

Fig. 4 is a side view of a switch unit designed for use in the system shown in Fig. 3; and

Fig. 5 is a front view of the device shown in Fig. 4 with some parts broken away.

Referring first to Figs. 1 and 2, the construction there shown comprises an electric gong mounted on a panel 2 and comprising a bell 3 with the usual vibrating hammer 4, and the customary, or any other suitable means, for actuating said hammer, said means being enclosed in the casing 5. In the arrangement shown, the panel 2 forms the front of a box or casing 6 in which a dry battery 7, or some other convenient source of electric current, such as a bell transformer, is mounted.

For the purposes of this invention, the operating circuit for the bell is controlled by a simple form of switch comprising a wire arm 8, a portion of which is wound around the screw 9 to form a spring 10, Fig. 2, the screw anchoring the spring to the panel. Cooperating with this arm are two stationary contacts *a* and *b*, both formed on, or secured to, a contact plate 12 which is screwed to the panel 2, and the arm carries a contact *c* positioned between the stationary contacts *a* and *b* and adapted to engage either of them. The free end of the spring switch arm 8 terminates in a hook 8" to which a length 13 of thermoplastic thread, string, cord, or other filamentary material, hereinafter referred to generically as "thread," is secured, its opposite end being fastened to a binding post 14.

According to this invention the thread 13 is

made of a copolymer of vinyl chloride and vinyl acetate. That available commercially under the name of Vynon fiber is preferred. It has the advantage of being exceptionally stable and unaffected by the common agents which might make it unreliable. For example, it is non-absorbent, non-inflammable, except upon direct exposure to flame, permanently water-resistant, mildew-proof, and is acid-proof for all practical purposes important in connection with this invention. While the unstretched Vynon yarn has a very low tensile strength, the stretched varieties are very strong. One form known as ST Vynon yarn is pre-stretched about 50%, while another, known as HST, is pre-stretched 100%. These both have surprisingly high tensile strength. Also, both have the characteristics, valuable for the purposes of this invention, of remaining very stable as to length, as their temperature is raised, up to about 148° F. At this point the thread contracts about 5% in length and contraction continues as the temperature rises until either the melting point of 260° F. is reached or the thread has contracted to its original length. Once contracted, the thread remains stable in length at decreasing temperatures. This characteristic is used in the apparatus shown in Figs. 1 and 2. Assuming that the assembly there shown is in operation, and the temperature of the thread 13 is raised to some point above 148° F., the thread will contract, thus bringing the contact *c* into engagement with the contact *b*. This completes a circuit from the battery terminal 15 through the conductor 16, spring switch arm 8, contacts *c* and *b*, and wire 17, through the bell solenoid and conductor 18, to the other battery terminal 20.

If the fire should reach the thread 13, or it should become broken for any reason, then the switch arm 8 is released, thus bringing the contact *c* into engagement with the contact *a* and closing the bell circuit again.

Thus the alarm is sounded either upon its rupture or overheating, that is the raising of the temperature of the thermoplastic thread 13 above the critical point in the neighborhood of 148° F.

Because of the nature of fibers made of the copolymer above designated, there is practically no danger of the thread 13 deteriorating sufficiently to render the device inoperative, and a very infrequent inspection of the apparatus is sufficient to determine the operativeness of the electrical elements of the apparatus.

The apparatus may be located in any con-

2

venient spot where it is believed that fire is most likely to occur as, for example, by hanging it on a hook, an aperture 21, Fig. 1, being provided in the casing 6 for this purpose. When it is desired to use any substantial number of these alarms located at different points in the building, a series of independent units, such as that shown in Figs. 1 and 2, may be employed, or a single unit of this nature may be connected up to a number of switch units so that the rupture or contraction of the controlling element 13 at any one of these points will sound the alarm.

A switch unit suitable for this purpose is shown in Figs. 4 and 5 in which the parts corresponding to those shown in Figs. 1 and 2 are designated by the same, but primed, numerals. Here the spring arm 8' is arranged as before with its contact c' operating between upper and lower co-operating contacts a' and b', and the plate 12', on which the latter are mounted, is provided with a terminal binding screw 22. The thread 13' is tensioned between the hook of the spring arm and the binding post 14'. For convenience in installation it is usually preferable to connect the spring 10' by a conductor 23 to a terminal screw 24 near the lower part of the support 2', the conductor preferably being mounted in a groove in the edge of said support.

A system in which a series of these switch units are mounted is illustrated diagrammatically in Fig. 3. Several of these units are there shown connected in parallel to the positive and negative conductors 25 and 26 leading from the opposite terminals of the battery 7, the bell unit 5 being connected into one of these conductors. Thus, if any one of the threads 13' contracts, due to a rise above its critical temperature, or should burn off or become broken, the alarm will immediately be sounded and warning given of the overheating or failure of one of the thermoplastic threads.

Thus the invention provides a very simple, reliable and inexpensive form of fire alarm which can be quickly installed by any one familiar with simple electrical circuits, or even by the householder himself.

While I have herein shown and described a preferred embodiment of my invention, it is contemplated that the invention may be embodied in other forms without departing from the spirit or scope thereof.

Having thus described my invention, what I desire to claim as new is:

1. An apparatus of the character described, comprising an electrically operated alarm device, an electric circuit in which said device is operatively connected, a switch in said circuit comprising a movable contact and two stationary contacts, said movable contact being located between said stationary contacts, a means connected with said movable contact and tending to move the latter into engagement with one of said stationary contacts, and a thread connected with said movable contact and holding it normally in its open position, said thread being composed essentially of a copolymer of vinyl chloride and vinyl acetate and being prestretched, whereby it operates upon overheating to shrink and thereby to close the circuit through one of said stationary contacts and upon rupture to close the circuit through the other of said stationary contacts.
2. An apparatus of the character described, comprising an arm carrying a switch contact, two additional contacts between which the contact movable with said arm operates, and a prestretched thread composed essentially of a copolymer of vinyl chloride and vinyl acetate connected to said arm and controlling the engagement of the latter contact with one of said additional contacts, whereby the rupture of the thread permits said arm to move its contact into engagement with one of said additional contacts and the shrinkage of said thread by overheating causes it to move said arm sufficiently to make its contact engage the other of said additional contacts, and yielding means connected with said movable contact for urging the same toward one of said additional contacts.

IVAR O. MOBERG.
